UNITED STATES PATENT OFFICE.

GEORGE R. DELAMATER, OF HARRISBURG, PENNSYLVANIA.

MINERAL SEPARATOR.

Application filed October 24, 1922. Serial No. 596,576.

This invention is a mineral separator adapted for wet and dry concentration. It is characterized, in its preferred form, by a table comprising a perforated plate or screen inclined from a source of mineral supply to means for controlling the discharge of the separated materials, having sides converging to provide a gradually contracting course of increased depth at the lower end thereof from the top of which the lighter of the separated materials are discharged over the sides or side gates and from the bottom of which the heavier of the separated materials is discharged through a pocket under control of gates, in combination with means for delivering and disseminating a pulsating fluid through the perforated bottom and the materials thereon to effect their movement and separation.

Desired results secured by my invention are the capacity for increasing the depth of the materials stratified in moving over the table in the contracted part or throat thereof, for separately discharging effectively separated materials from the top and bottom of this deep section without discharging any "middlings" therewith and generally for effectively separating materials of widely varying percentages of refuse or concentrates, free of middlings heretofore discharged and requiring reworking, by an apparatus and operation that is simple and inexpensive as well as superior in efficiency.

A preferred form of apparatus adapted for the practice of the invention is set out in the following description and the accompanying illustrations thereof.

In the drawings, Fig. 1 is a plan view of the apparatus; Fig. 2 is a vertical sectional view taken on the line 2^x-2^x of Fig. 1, and Fig. 3 is a front elevation of the construction.

In the apparatus illustrated in the drawings, a hopper A, having the bottom valve B, is supplied with the material to be separated, as coal mixed with heavier refuse or ore mixed with lighter refuse.

An inclined screen or perforated plate C is supported, with its top beneath the hopper A, by the frame D provided with transverse members D', D'', D'''. Boards E are supported by the frame at the sides of the screen and extend downwardly from the hopper on opposite sides of the valve the distance over which the material will move in

the operation of stratifying it, these boards or sides being of sufficient height to prevent such material from escaping thereover. Fixed plates E' and adjustable gate boards F extend in converging relation from the boards E downwardly to provide a downwardly tapering course or section with side gates or weirs at the lower end of the channel formed by their combination with the sides E and the screen C. A frame G supported above the relatively flat lower end section C' of the screen combines with the frame D and sides E to support the plates E' and gates F. The plates E' are overlapped by the gates F in the lower positions thereof, and the gates are adjusted to such positions that their horizontal tops will have the elevation appropriate to the material to be treated and the general design of the machine, involving the inclination of the screen C, the distance between the boards E and the angular relation of the parts F, such parts being adjustable vertically along the end guides F' and F''.

A gate H, of angular horizontal cross-section adapted to divide the lighter separated materials, extends between the lower ends of the gates F and is adjustable in the vertical ways H' to provide the desired opening between its bottom and the screen for the passage of the concentrates of heavier materials, the lighter material working over the tops of the side gates. A gate I extends across the lower end of the screen C between the sides of the frame G and is movable vertically in the ways I' to control the discharge of the concentrates that work under the gate H into the pocket J, formed by these gates together with the sides of the frame G and the lower end of the screen C. A chute K, fixed to the sides of the frame G at the lower end of the screen C, is adapted for discharging the concentrates which work under the gate H, into the pocket J and over the gate or weir I.

Perforated plates or screens L, L' and L'' are set in the frame D across the spaces of different cross-section separated by the parts D' and D''. Chambers or hoppers M, M' and M'' taper downwardly from these plates which extend across or over the tops of said hoppers. Conduits N, provided with the respective regulating valves N', connect the hoppers with the main conduit O containing a rotary valve P' through which a pulsating

fluid, as air, is supplied from a compressor P. The pulsating fluid expands in the respective chambers M, M' and M'' and flows thence through the disseminating screens L, L' and 5 L'' of decreasing areas to corresponding sections of the screen C and section of the minerals thereon.

This construction permits the force of the fluid to be adjusted so as to effect the appropriate lifting force upon successive sections of the materials and the movement of the materials from the hopper A, over the screen C, with stratification of each material, the discharge of the separated lighter material 10 over the gates F and of the heavier material under the gate H, through the pocket J and over the gate I. The areas of the screens L' beneath the materials between the gates F are made smaller than those of the screens L 15 beneath the materials between the sides E, and the still smaller screen L'' as well as the cross section of the space between the parts D'' are directly beneath and substantially the same as the cross-section of the pocket J. 20 25 In operation, the materials to be separated are delivered from the hopper A under the valve B properly adjusted to regulate the feed over the screen C, the perforations of which are of such size as to prevent the passage of the materials therethrough, air (for the use of which the design is appropriate) flowing from the tank P through the rotat- 30 ing valve P', the conduits O and N, the chambers M, M' and M'', the screens L, L' 35 and L'' and the screen C. The pulsations of the compressed air of suitable pressure, say from 60 to 100 pounds per square inch, effects the movement of the materials over the screen C and the stratification of such materials. 40 These materials are in stratified condition when they reach the throat or contracting lower section of the table and the bed of materials becomes deeper as it passes therethrough so that at the lower end of said 45 throat, where the concentrates or heavier materials escape under the gate H, such heavier materials alone escape, as the middlings or imperfectly separated materials will lie between the controlling edges of the 50 gates F and H with room to move vertically under the forces to which they are subjected appropriate to their depth and separate effectively within the throat so that the lighter material as coal will be carried over 55 the gates F and the heavier refuse under the gate H, both free of middlings. The seal of heavier materials in the pocket J is subjected to the pulsatory action appropriate thereto by the relatively small passage therefor and 60 is moved thereby and by the pressure of the materials flowing under the gate H, over the gate I.

Separations can be effected in this manner without the necessity for reworking middlings, which are worked in the operation. 65

though there may be a large amount and wide variation in the content of concentrates or refuse.

Having described my invention, I claim:—

1. In a mineral separator, an inclined 70 screen having sides providing a channel that has a lower contracting section of increasing depth, a gate extending across said section at the lower end thereof with its lower edge disposed so as to permit the movement there- 75 under of materials on said screen, and a second gate with its upper edge disposed above the lower edge of said gate first named so as to form therewith a mineral seal between said gates. 80

2. In a mineral separator, an inclined table comprising a channel having a perforated bottom and a contracted section with a side gate for the discharge of the lightest of the separated substances from the top of 85 the bed in said section, a gate extending across the lower end of said channel above the bottom thereof between which the heaviest of the separated substances is discharged from the bottom of the bed and a 90 gate coacting with said gate second named to provide a pocket for holding a seal of said heaviest substance and for permitting the top of said seal to escape thereover. 95

3. In a mineral separator, a table having a perforated bottom, a gate under which the heaviest of the substances is discharged from the stratified bed on said bottom, a gate ex- 100 tends from said perforated bottom to the lower edge of and coacting with said gate first named to provide a pocket for holding a seal of said heaviest substances, means comprising a passage under said pocket for distributing a fluid under pressure through said bottom and means for pulsating said 105 fluid. 100

4. In a mineral separator, a table having an inclined perforated bottom, gates at the lower end thereof, adapted for holding a mineral seal for the bed of minerals on said bottom, perforated means beneath said bottom, members forming passages of different cross sectional areas for delivering a fluid under pressure through said means and bottom, and means for pulsating said fluid. 110 115

5. In a mineral separator, a table having an inclined perforated bottom, gates at the lower end thereof cooperating to form a pocket to which the heavier of the separated substances is adapted to pass under one of said gates and from which said substance is permitted to escape over the other of said gates, and means for delivering pulsating fluid pressure through said bottom to stratify materials thereon and to the mate- 120 rial in said pocket, said means comprising passages beneath said bottom diminishing in cross section toward the lower end thereof, including a passage below said pocket of approximately the same cross sectional area, 125 130

as said pocket, screening means extending across said passages, and means for regulating the fluid flowing through said passages.

6. In a mineral separator, a table having an inclined perforated bottom, gates at the lower end thereof for controlling the discharge of separated materials from the stratified bed on said bottom, a pocket for holding a seal of the heaviest of said materials delivered thereto under one of said gates and therefrom over another of said
- gates, hoppers beneath said bottom diminishing in cross sectional area toward the lower end of said table, conduits provided with valves for delivering a fluid under control ¹⁵ to said hoppers and bottom and means for delivering pulsating fluid pressure through said conduits.

Signed at Harrisburg, in the county of Dauphin and State of Pennsylvania, this ²⁰ 21st day of October, 1922.

G. R. DELAMATER.
